DESIGN FOR A BATHROOM SCALE

Dave Chapman, Chicago, Ill., assignor to Hanson Scale Company, Chicago, Ill., a corporation of Illinois

Application May 3, 1945, Serial No. 119,383

Term of patent 14 years

(Cl. D52—10)

To all whom it may concern:

Be it known that I, Dave Chapman, a citizen of the United States and resident of Chicago, in the county of Cook and State of Illinois, have invented a new, original, and ornamental Design for a Bathroom Scale, of which the following is a specification, reference being had to the accompanying drawings, forming part thereof.

Fig. 1 is a top plan view of a bathroom scale showing my new design.

Fig. 2 is a front elevational view.

Fig. 3 is a side elevational view.

Fig. 4 is a rear elevational view thereof.

I claim:

The ornamental design for a bathroom scale,
as shown.

DAVE CHAPMAN.
